UNITED STATES PATENT OFFICE.

VINCENT SCALZO, OF PITTSTON, PENNSYLVANIA.

WINDSHIELD CLEANER.

Application filed April 19, 1927. Serial No. 184,957.

The present invention relates to cleaning devices for use in cleaning glass surfaces, and more specifically to an improved cleaner for use in removing dust and the like from the windshields of motor vehicles.

The primary object of the invention is to provide a novel and improved type of heated windshield cleaner.

A further object of the invention is to provide a novel type of windshield cleaner embodying means whereby the device may be heated for the effective removal of snow and ice from the windshield when driving in inclement weather.

15 A further object of the invention is to provide a novel type and improved type of electrically heated windshield cleaner which may be readily attached to the usual arm of cleaner actuating mechanisms as now in common use for movement of the cleaner across the surface to be cleaned.

20 A still further object of the invention is to provide an improved electrically heated windshield cleaner which will be of extremely light yet durable construction and one wherein the heating medium or element is readily removable from its carrier portion.

25 A still further object of the invention is to provide an improved electrically heated windshield cleaner embodying a novel arrangement whereby the heat is effectively directed toward the glass over which the cleaner is moving without any likelihood of the heat becoming too great and resulting in possible breaking of the glass.

30 Other objects and advantages of the invention will be apparent during the course of the following detailed description, taken in connection with the accompanying drawing, forming a part of this specification and in which drawing:

35 Figure 1 is a central longitudinal section thru the improved cleaner and showing the manner in which the same may be mounted upon an arm of the conventional type of cleaner actuating means.

40 Figure 2 is a plan view looking at the inner open side of the cleaner and showing fragmentary portions broken away for illustrating certain details of construction.

45 Figure 3 is a fragmentary perspective view of the outer end of the back or frame of the cleaner and showing the closure cap for closing the outer end of the frame.

50 Figure 4 is a transverse section on line 4-4 of Figure 1.

Figure 5 is an end view of the cleaner and looking at the same from its outer end.

55 Figure 6 is a perspective view of the clip for attachment of the cleaner to the actuating arm of a cleaner operating mechanism.

Figure 7 is a perspective view of the core of the heating element and showing the same broken away at its inner end for illustrating the construction of the inner end of the core.

60 Referring to the drawing in detail, and wherein similar reference characters designate corresponding parts thruout the several views, the improved cleaner is shown as embodying a back or frame A provided with spaced wiping elements B, and a removable heating medium C.

65 Referring first to the construction of the back or frame A, the same is preferably formed from sheet metal of a suitable grade 70 formed to provide arcuate outwardly bulged longitudinal side walls 10 forming a substantially tubular housing extending thruout the length of the frame. The inner or free edges of the walls 10 are bent to provide parallel longitudinal attaching flanges 11 which also extend thruout the length of the back. These longitudinal flanges 11 are suitably spaced from one another for forming the longitudinally extending opening 75 as at 12, and it is preferred that the flanges have a normal tendency to spring toward one another so as to afford a proper gripping action upon the heating medium C. The metal at the outer or connecting ends of the 80 side walls 10 is bulged outwardly for forming a channel-like rib 14 which also extends thruout the length of the back A, and this rib aside from serving a function to be subsequently explained, further acts as a reinforcing means for the elongated frame. Thus it will be seen that the body portion 85 of the back or frame A may be easily formed from a rectangular shaped piece of sheet material for formation of the substantially 90 tubular way 15 being open at its inner side and closed at its outer side by the longitudinally extending channel-like rib 14. The inner end of the open way 15 is preferably 95 closed by means of a flat cap plate 16 of a configuration conforming to the end formation 100 of the back, and which cap plate is provided at its inner edge with inwardly extending apertured ears 17 which are adapted to be secured to the flanges 11 as by means 105 of suitable rivets 18 preferably having counter-sunk heads at their connections

110

with the flanges 11. The cap plate 16 aside from providing a closure for the inner end of the way 15 also serves as a positive spacing means for the inner ends of the flanges 11.

A U-shaped attaching clip 18 is preferably riveted to the walls 10 at their juncture with the rib 14, and preferably at the longitudinal center of the frame as illustrated in Figure 1. This U-shaped clip 18 is apertured as at 19 for receiving a suitable wing nut 20 whereby the arms of the clip may be rigidly clamped about an actuating arm 21 of a suitable cleaner operating mechanism. The arm 21 may have movement imparted thereto in any suitable manner for movement of the cleaner across the windshield either in an arcuate path or for movement of the cleaner transversely across the windshield.

The wiping elements B, and one of which is intended to be carried by each of the spaced flanges 11, each embodies a U-shaped carrier portion 23 adapted to be clamped about one longitudinal edge of suitable wiper blades 24 formed of any suitable material such as rubber or cloth. The wiping elements B are secured longitudinally at the outer face of each of the flanges 11 as by means of suitable bolts and nuts 25, and as will be observed, the wiping elements are secured to the flanges at their longitudinal centers as by a single bolt and nut 25. This single attaching means for the wiping elements will allow for slight pivotal movement of the wiping elements about the bolts 25 and insure proper edge contact of the blades 24 with the windshield glass. As will be observed, the spaced wiping elements B extend thruout the length of the frame A at each side of the opening 12.

The heating medium C and which is adapted to be readily removable from the frame A, embodies an elongated core 28 of insulating material such as porcelain or the like, and which core is of tubular formation and provided with a longitudinally extending slot 29 which extends thruout the entire length of the core. The outer end of the core 28 is externally enlarged as at 30 for forming suitable bosses which will engage the outer end of the frame A for limiting inward movement of the core within the tubular way 15. As will be observed in Figure 1, the core 28 is of less length than the frame A and thus when the bosses 30 engage the outer end of the frame, the inner end of the core is spaced a suitable distance from the cap plate 16. The tubular insulating core 28 when inserted into the frame A, has its slot 29 aligning with the inner end of the opening 12 as clearly illustrated in Figure 4. The core 28 is intended to serve as a suitable carrier for a heating element 35 preferably in the form of a resist-

ance wire being crimped intermediate its ends as at 36. This wire heating element 35 extends thruout the length of the core 28 and is attached at its inner end to a suitable bolt 37 mounted in suitable insulating washers 38, and at its outer end attached to a suitable bolt 39 mounted in suitable insulating washers 40. These bolts 37 and 39 serve as terminal binding posts for electrical conductors 41 and 42 respectively, and which conductors may pass thru a suitable switch to a source of electrical energy such as the battery of the vehicle.

The conductor 42 is connected to the bolt 39 at the outer end of the core, while the conductor 41 extends longitudinally of and externally of the core for attachment to the bolt 37 at the inner end of the core. Thus it will be seen that when the heater is inserted into the frame A, that the channel-like rib 14 provides a space for accommodating that portion of the conductor 41 which extends longitudinally of and externally of the core 28. When the heater is inserted in the frame A with the conductor 41 in the channel rib 14 and the bosses 30 engaging the outer end of the frame, the yieldable walls 10 of the frame will grip the core 28 sufficiently for preventing rotation of the core or movement of the core longitudinally out of the frame.

The object in so crimping the resistance wire 35 at the longitudinal center of the core 28 is to provide more heating area at the center of the cleaner for effectively cleaning snow and ice from the windshield without excessive heating of the conductors 41 and 42 at their connections with the terminal bolts 37 and 39. As will be observed in Figures 1 and 4, the flanges 11 and wiper blades 24 will cause the heat from the wire 35 to be directed thru the opening 12 and thus spaces the wire a sufficient distance from the windshield as to eliminate possibility of the glass being heated to a degree whereby the glass would be apt to crack.

As will be seen, when the cleaner is moved across the windshield by means of the arm 21, that heat from the element 35 will serve to effectively remove snow and ice from the windshield glass and thus allow the operator to have a clear vision thru the windshield.

By so having the heating medium C so removably carried by the frame A, permits of the ready removal of the heater should it become necessary to renew the wire 35 and will also allow for the heater to be removed from the frame during the summer months is so desired.

From the foregoing description it will be apparent that an improved and novel type of electrically heated windshield cleaner has been provided embodying a rigid frame construction which may be economically formed from sheet material, and embodying a heat-

ing medium readily removable from the frame for the ready making of repairs, and which supporting frame is of such novel construction as to allow for the current conducting wires to be readily attached at opposite ends of the heating medium and not materially affected by the heat generated by the heating element.

Changes in the shape, size, and arrangement of parts may be made to the specific form of the invention herein shown and described, without departing from the spirit of the invention or the scope of the following claims.

15 1 claim:

1. A windshield cleaner comprising a channel-like frame having yieldable outwardly curved side walls provided at their free edges with flanges extending in spaced parallel relation, a wiping element carried by each flange, and a heating element having a tubular casing insertable into said frame between the yieldable side walls from one end thereof and having a longitudinally extending opening aligning between said flanges.

2. A windshield cleaner comprising an elongated resilient body of channel-like formation having a restricted opening and providing a pair of parallel spaced apart flanges, a wiping element carried by each flange, and a heating element embodying a tubular insulating core slidably fitting in the resilient body and provided with a longitudinally extending slot opening between said flanges, and a resistance wire extending longitudinally in the tubular insulating core.

3. A windshield cleaner comprising a sheet metal channel-like frame having outwardly bulged side walls forming at their free edges a pair of parallel spaced apart flanges, a cap closing the inner end of the channel-like frame, a wiping element carried by each flange and each embodying a wiper blade projecting past the free edge of the flange, and a heating element having a core removably insertable into the channel-like frame from the outer open end thereof and provided with a longitudinally extending slot opening between said flanges.

4. A windshield cleaner comprising a channel-like frame formed with a pair of parallel spaced apart flanges extending longitudinally of the frame, elongated wiping elements extending longitudinally of each flange, a single fastening element connecting each wiping element at its longitudinal center to the longitudinal center of each flange, and a heating element arranged in the frame and including a core having an elongated opening aligning between said flanges.

5. A windshield cleaner comprising an elongated frame of channel-like formation providing outwardly bulged side walls con-

nected at their outer edges by a longitudinally extending hollow rib and having parallel spaced apart flanges at the inner edges of the side walls, a wiping element carried by each flange, an insulating core arranged between the side walls with a slot opening between said flanges, and forming a longitudinally extending way at said rib, a heating wire extending longitudinally within the core and connected with terminals at the inner and outer ends of the core, a conductor wire connected with the terminal at the outer end of the core, and a second conductor wire extending thru said way for connection with the terminal at the inner end of said core.

6. A windshield cleaner comprising an elongated substantially tubular body having outwardly arcuated yieldable side walls connected at their outer edges by a hollow channel-like rib and having their inner converging edges spaced for providing parallel spaced apart flanges, a wiping element carried by each flange, and a heating element removably insertable into said body between said outwardly arcuated side walls and having a conductor wire extending externally and longitudinally thereof for fitting in said hollow channel-like rib, said conductor having electrical connection with the inner end of the heating element.

7. A windshield cleaner comprising a channel-like frame formed with a pair of parallel spaced apart flanges and provided with a longitudinally extending outwardly formed rib, a U-shaped attaching clip secured longitudinally of the frame with the arms thereof embracing said rib, a wiping element carried by each flange and held in parallel spaced relation thereby, and an electric heating element embodying a longitudinally slotted core removably insertable into said frame from one end thereof and having a conductor terminal extending longitudinally at the interior thereof for fitting in said rib.

8. In a windshield cleaner including a frame of channel-like formation for providing an open side, heating means for the cleaner embodying a tubular core insertable into said frame and provided with an enlarged outer end serving to limit movement of the core into the frame, said core being slotted longitudinally with the slot being adapted to align with the open side of the channel-like frame, a resistance wire extending longitudinally within the core and mounted at opposite ends in inner and outer terminal bolts, and a conductor wire connected with each terminal bolt for heating of the resistance by the passage of an electric current therethru.

9. In a heated windshield cleaner embodying an open sided frame, and wiping elements carried in spaced relation longitudi-

- nally of the frame at the open side thereof, a tubular insulating core removably insertable into the frame from one end thereof and provided with a longitudinally extending slot for aligning with the open side of the frame between the wiping elements, and an electrically heated resistance wire extending longitudinally within the core.
- 5 10. In a heating element for windshield cleaners including an open sided frame and
- wiping elements carried in spaced relation upon the frame, an elongated tubular insulating core being slotted longitudinally, insulating washers ranged over each end of the core, terminal bolts carried by the washers at each end of the core, and a heating wire connected at its opposite ends to the terminal bolts and provided midway of its ends with a crimped portion.

15 VINCENT SCALZO.
